ATTORNEY

UNITED STATES PATENT OFFICE.

CLYDE A. RICKARD, OF OTTAWA, KANSAS.

STEAM-BOILER FEEDER.

SPECIFICATION forming part of Letters Patent No. 313,954, dated March 17, 1885.

Application filed May 16, 1884. (No model.)

To all whom it may concern:

Be it known that I, CLYDE A. RICKARD, a citizen of the United States of America, residing at Ottawa, in the county of Franklin and State of Kansas, have invented certain new and useful Improvements in Steam - Boiler Feeders, of which the following is a specification, reference being had therein to the accompanying drawings.

10 This invention relates to that class of steam-boiler feeders in which the water is fed from a tank or reservoir by gravity; and it consists in the peculiar construction and arrangement and combinations of parts, hereinafter more particularly set forth and claimed.

15 In the accompanying drawings, Figure 1 is a side elevation of a boiler with portions broken away, showing my improvements attached. Figs. 2 and 3 are details showing the construction of modifications of the piston.

20 A represents a furnace, and B a boiler located within the same, both of which may be of any well-known construction; but for my purpose I prefer a sheet-metal furnace and a spiral tube, 25 as shown.

A' is a reservoir or tank, the upper and lower portions of which are connected with the steam and water space of the boiler B, respectively.

30 C' are the heads, connected to the main body of the reservoir by bolts or rivets, a steam-packing being inserted between the parts to make a close joint.

D is an escape-vent connected to the head 35 C, and provided with a valve, d.

E is a supply-pipe attached to the lower part of the tank A', and has a suitable valve, e.

40 P is a piston fitting steam-tight within the tank, the rod p of which extends within the tube F, and is guided therein by the ribs f, extending inwardly from the casting F', which is secured to the head C, and receives the end of the tube F. This piston is provided with packing G, and with automatic exit H, for the water of condensation, which, as shown in Fig. 45 2, consists of a siphon, S, the long leg of which extends below the head, while the shorter limb enters a recess, I, formed within the head.

Fig. 2 shows a floating piston, which may 50 be made of wood, while Fig. 3 shows a floating metallic piston, whose interior may be filled with some light material, J, that is a bad con-

ductor of heat, or it may have a coating, j, of plaster-of-paris or other bad conductor on its top.

55 In practice, when more water is required, the valves d and e being opened and the valves f' and b closed, water is fed in through E and fills the tank A', and causes the piston to rise to the position as shown, the air above the piston escaping through the pipe D. When the tank is filled and the valves d and e closed and the valves f' and b opened, the water passes to the boiler B, and is there converted into steam, an equilibrium being established 60 in the tank through the connections already described. A pipe, M, connected to the free end of the T-shaped casting L, attached to the outer end of the coil B, conveys the steam from the boiler to be applied for cooking, heating, 65 motive power, or any purpose for which steam is applicable.

70 It will be seen that by my construction a cheap and simple apparatus is produced that can be applied to many purposes—such as 75 for cooking feed, heating, furnishing motive power, &c.

75 My peculiar arrangement of the steam-tight piston prevents the steam coming in contact with the cool water, and thus prevents condensation, and the non-conducting material prevents the rapid condensation caused by the contact with the surface of the cool piston, and thus much fuel is saved which is lost by the usual construction, where the steam comes 85 in direct contact with the water and a piston cooled by the water below it.

80 I am aware of E. Campbell's Patent No. 2,233, dated August 28, 1841, and make no claim to anything shown therein.

90 What I claim is—

1. In combination with a steam-boiler, a reservoir provided with steam and water spaces in direct communication with the steam and water spaces of the boiler, respectively, and 95 a piston working steam-tight in said reservoir for separating the two elements within the same, substantially as and for the purpose described.

2. In combination with a steam-boiler and its reservoir, a steam-tight piston fitting within said reservoir, and provided with an automatically-operated exit, as H, substantially as and for the purpose specified.

3. In combination with the reservoir A' and the steam-tight piston P, the siphon S and recess I, substantially as and for the purpose specified.

5 4. In combination with the reservoir A', piston P, and rod p, the casting F', provided with the ribs f, substantially as and for the purpose specified.

In testimony whereof I affix my signature, in presence of two witnesses, this 12th day of May, 1884.

CLYDE A. RICKARD.
